UNITED STATES PATENT OFFICE.

LELAND S. LAUFENBURG AND SYLVESTER G. PEARSON, OF STOCKTON, CALIFORNIA.

ENGINE-SUPPORTING FRAME.

1,072,743.

Specification of Letters Patent.

Patented Sept. 9, 1913.

Application filed September 5, 1912. Serial No. 718,644.

To all whom it may concern:

Be it known that we, LELAND S. LAUFENBURG and SYLVESTER G. PEARSON, citizens of the United States, residing at Stockton, 5 in the county of San Joaquin, State of California, have invented certain new and useful Improvements in Engine-Supporting Frames; and we do declare the following to be a clear, full, and exact description of 10 the same, such as will enable others skilled in the art to which it appertains to make and use the same, reference being had to the accompanying drawings, and to the characters of reference marked thereon, 15 which form a part of this application.

This invention relates to improvements in engine supporting frames, the main object of the invention being to produce a portable engine supporting frame adapted to receive 20 engines or motors of all kinds for the purpose of working upon the same for making repairs or similar work.

A further object of the invention is to produce an underslung frame mounted in 25 said portable frame and capable of being revolved around a pivotal point in any desired manner in order to enable any part of the engine or motor to be reached. Said underslung frame may be made, as will appear, 30 so that it can be adjusted to such a nicety with respect to the weight of the engine or motor that such engine will so hang in the frame as to permit the same to be turned in a complete circle without any 35 effort whatsoever.

A further object of the invention is to produce a simple and inexpensive device and yet one which will be exceedingly effective for the purposes for which it is 40 designed.

These objects, we accomplish by means of such structure and relative arrangement of the parts as will fully appear by a perusal of the following specification and claims.

45 In the drawings similar characters of reference indicate corresponding parts in the several views.

Figure 1 is a side elevation of the complete device. Fig. 2 is an end elevation of 50 the same. Fig. 3 is a detached view shown in section on a line Y—Y of Fig. 1. Fig. 4 is a sectional view taken on a line X—X of Fig. 3.

Referring now more particularly to the 55 characters of reference on the drawings, the numeral 1 designates said supporting frames

mounted on beams 2 which may or may not be provided, as found desirable, with supporting rollers or wheels 3. Each of the frames 1 is provided with a vertical arm 4 for the purpose as will appear.

Journaled in the upper ends of the frames 1 are pins 5, secured to the ends of which are disks 6 provided with a plurality of holes 7 in their sides. The engine supporting frame is secured to said disks 6 in the following manner: The side frames 8 of said engine supporting frame are provided with vertical slots 9 projecting through which are bolts 10 having nuts 11 by means of which bolts and nuts, the said members 8 are secured to the disks 6. The bolts 10 are slidable through the slots 9, whereby said members 8 may be adjusted to any desired position on said disks 6. In order to aid in this adjustment, if desired, we will provide inwardly projecting arms 12 on top of the disks 6 through which will be mounted set screws 13 turnably connected with the upper ends of the members 8, whereby by moving said set screws 13 the said members 8 will be raised or lowered, any fixed position of the same being determined and held by means of the bolts 10 and nuts 11. The members 8 are braced together by means of angle iron cross bars 14 which are rigidly secured to the members 8 in any desired manner.

The lower ends of the members 8 are provided with slotted guides 15 in which are 90 slidable bolts 16, which bolts 16 project upwardly between two cross beams 17 spaced apart on each side of said bolts 16 and adapted to be connected by cross bolts 18. These members 17 as will be readily seen, 95 are adjustable along the lower edges of the members 8 and are adapted to receive the engine or motor, which engine or motor would be connected to said beams by means of bolts projected through the lugs of said 10 engine and motor and between said member 17 and be secured thereto by means of nuts mounted on said bolts. Any desired fixed position of the members 17 on the members 8 is obtained by tightening nuts 19 in the upper end of the bolts 16.

In practice the engine or motor would be secured to the members 17 in the manner set forth and then the members 8 would be adjusted on the disk 6 at such point as to cause 11 said engine or motor to be perfectly balanced on the pivotal points 5 which would then

permit such engine or motor to be readily turned in any direction without a great deal of effort, whereby all parts of the engine or motor could be easily reached for any purpose desired. Any fixed position of the engine or motor could be held by means of pins 20 projecting through the arms 4 and engaging the holes 7.

While we have shown and described the device as having the adjustable features of the underslung engine frame, still if desired such engine frame without any adjustment could be pivotally swung on the members 1 and be used in that manner with the same effect, there being means of course of fixing it in desired position in its rotation.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the scope of the claims.

Having thus described our invention what we claim as new and useful and desire to secure by Letters Patent is:

1. A device of the character described comprising the combination of a supporting frame, a pair of disks pivotally mounted on

said supporting frame, independent frame members adjustably mounted on said disk, and supporting beams adjustably disposed on said independent frame members, as described.

2. A device of the character described comprising a supporting frame, a pair of disks pivotally mounted on said frame in spaced relation, bolts disposed in said disks and provided with nuts, independent frame members provided with slots mounted over said bolts, and supporting beams disposed in said independent frame members, as described.

3. A device of the character described comprising a supporting frame, a pair of disks pivotally mounted on said frame in spaced relation, independent frame members mounted between said disks and being capable of sliding adjustment thereon, projecting arms on said disks, set screws disposed in said arms and engaging said independent frame members and supporting beams mounted on said independent frame members, as described.

In testimony whereof we affix our signatures in presence of two witnesses.

LELAND S. LAUFENBURG.
SYLVESTER G. PEARSON.
